CLOSURE CAP AND POURING SPOUT UNIT

Myron D. McCauley, Huntington Woods, Mich.,
assignor to Rinshed-Mason Company, Detroit,
Mich., a corporation of Michigan

Application February 28, 1947, Serial No. 731,494

2 Claims. (Cl. 222—80)

1

This invention relates to a device applicable to a container of liquid substance for the purpose of agitating and mixing the substance and dispensing the substance from the container.

More specifically, the invention has to do with the provision of an improved device applicable to paint cans. When the device is applied to a paint can it may be operated to agitate and mix the contents, and then the paint may be poured from the can by means of a dispensing spout. The term "paint" is used herein as broadly significant of coating materials, including those specifically known as paint, and others which may technically be lacquer, shellac, varnish, or other related materials.

One of the objects of the invention is to provide a device which is quickly and easily applied to a container and which is equipped with agitating means of a novel structure for setting up a type of circuitous flow of the contents in order to agitate and thoroughly mix the same. In this connection blades are applied to a rotating element and while the blades are of a simple structure and form, they are so disposed and related to each other as to effect a thorough agitating and mixing action. A further object is to provide an improved pouring spout with a closure therefor, so formed and designed that when the pouring ceases the closure effectively cuts the stream and minimizes the formation of drops or other portions which may cling to the spout and later fall or run downwardly therefrom. A still further object of the invention is to provide a closure cap and pouring spout arrangement from which the contents may be poured without the use of a vent opening. A structure made in accordance with the invention is disclosed in the accompanying drawings.

Fig. 1 is a cross sectional view of the improved device showing the same applied to a container.

Fig. 2 is a view looking substantially on line 2—2 of Fig. 1 showing the agitating blade arrangement.

Fig. 3 is a top plan view taken substantially along line 3—3 of Fig. 1 showing the top of the closure and the container.

Fig. 4 is a sectional view taken substantially on line 4—4 of Fig. 3 showing one of the elements for attaching the structure to a container.

Fig. 5 is a sectional view taken substantially on line 5—5 of Fig. 1 showing the formation of the upper agitating blades.

Fig. 6 is a view showing the mouth of the pouring spout and taken substantially on line 6—6 of Fig. 1.

2

Fig. 7 is a sectional view taken substantially on line 7—7 of Fig. 4 illustrating the structure of one of the securing devices.

As illustrated in Fig. 1, a container, which may be a can for containing paint or similar material, is illustrated at 1 having a bottom portion 2 and an inwardly extending rim 3 provided with the usual downwardly extending flange or bead 4 which defines the opening in the can. Ordinarily a can top fits in the opening defined by the flange 4 which may be circular, but in Fig. 1 the closure cap is applied thereto.

This cap, which may be of die-cast metal, is generally indicated at 6, is of dome formation and it has a flange 7 designed to fit within the flange 4 and a top flange 8 designed to overlap the rim 3. The cap is equipped preferably with two attaching devices, which will be appreciated by reference to Figs. 3 and 4, and to this end the cap 15 has oppositely disposed bushing or bearing portions 10, in each of which is journaled the shaft part 11 of an attaching device. Each attaching device has a handle portion 12 which is exposed above the cap and a cam element 13 attached to the shaft 11 on the underside of the closure. The cam elements, as shown in Fig. 3, are 20 segmental in shape so that by turning the handle 12 they may be caused to project so as to underlie the flange 4 and may be arranged to project inwardly in order to apply the closure to the can and remove the same from the can. Each cam element 13 has an inclined or cam face 14 designed to engage under the flange 4, as shown in Fig. 7. Accordingly, to apply the closure it is 25 positioned as shown in Fig. 1 and then the handles 12 are manipulated to rotate the shafts 11 and swing the cams so that they frictionally engage with cam action under the flange 4.

In the central portion of the closure is a bearing formation 20 designed to receive a shaft 21 and a seal may be provided by a cap 22 screw threaded to the bearing portion and having an interposed washer 23. The exposed end of the shaft is provided with a handle 24 which may 30 be equipped with a finger piece 25 for rotating the same, and the shaft extends downwardly into the vessel, as illustrated.

The shaft carries the agitating elements. There is an upper and a lower agitating element, 35 as shown in Fig. 1. The upper element is advantageously formed from sheet metal having a central portion 27 formed to fit the shaft 21. This central portion is somewhat semi-circular in shape so as to embrace the shaft, and it may be 40 soldered or spot welded thereto. Extending lat-

erally from the central portion is a blade 28 and a blade 29. The main portion of the blade 28 extends upwardly and slightly angularly, as shown in Fig. 5, while the top thereof is curved to provide a forwardly extending leading edge 32. The opposite blade 29 is similarly shaped and it has a forwardly extending leading edge 31. The upper portions of the two opposite blades are thus oppositely curved. Considering the blade 28 as viewed in Fig. 5 and considering that its direction of movement is from right to left, in the direction of the arrow shown, it will be seen that the contents of the can into which the blade moves is engaged thereby and impelled downwardly by the formation of the blade. Since the blade 29 is on the opposite side, its movement, as Fig. 5 is viewed, is from left to right, and this blade, by its similar formation, urges the liquid contents downwardly.

The two lower blades are of similar construction except reversed. There is a central part 35 for attachment to the shaft, and an inclined blade 36 with its curved lower structure forming the leading edge 37. The opposite blade 38 is similarly inclined and curved to form its lower leading edge 39. By reference to Fig. 1 it will be observed that if the handle 24 is rotated clockwise, as Fig. 2 is viewed, the blade 36 scoops up the material by its leading edge 37 and impels the material upwardly. The blade 38 performs a similar function on the opposite side of the shaft, impelling the material upwardly as its leading edge 39 leads into the substance.

Accordingly, rotation of the mixing device thoroughly agitates the material as the portions in the lower part of the container are moved in a stream upwardly and the portions in the upper part are impelled downwardly, and the upwardly and downwardly mixing streams or masses engage each other, resulting in a thorough turning over of the contents and intermixing with each other.

The cap has a pouring spout formed integral therewith, the walls of which are shown at 40, thus providing a passage 45. For closing the spout there is a closure piece 41 for fitting over the end thereof and this closure piece is preferably integrally formed with an operating lever 42 provided with an aperture 43 through which the shaft 21 extends and having a free end 44 by means of which the same is manipulated. This closure piece or valve member is pivotally mounted as at 46 on lugs 47 formed on the cap and is actuated into closed position by a spring 48 coiled about the axis member and having extending portions engaging the wall 40 and the underside of the lever portion 42, as indicated. The rim or edge of the pouring spout is very accurately formed, as shown in Figs. 1 and 6. The metal defining the rim is preferably fashioned to provide a relatively sharp exposed edge 50, and it is further shaped to provide a narrow channel which advantageously has its central portion in somewhat of an apex, as shown at 51. The structure thus, as shown in Fig. 6, has the appearance of a relatively wide V. The element 41 is arranged to seat nicely on the relatively sharp edge 50. The end of the spout is conveniently formed so that it lies in a plane of about 30° from the vertical, as shown in Fig. 1, and the metal forming the end of the spout is fashioned as by means of suitable working operations to provide the sharp edge 50. As shown in Fig. 1, the metal adjacent the sharp edge and

adjacent the apex 51 may be about 45° from the horizontal.

In pouring the substance from the container, the operator needs but to depress the lever portion 42, thus swinging the member 41 from its seat so that the contents may be poured from the spout. When the lever 42 is released the spring 48 serves to close the spout. As the element 41 moves against its relatively sharpened seat 50 it efficiently cuts off the flow of the material. Due to the formation of the V structure with the apex at 51, the last portion of the stream of material is effectively severed with a sharp, clean action, upon the closing of the member 41, so that substantially no droplet or body of material remains on the spout.

The cap and spout structure provides for readily pouring the substance from the container without a gurgling or bubbling action and without the use of a vent. In this connection, it will be noted that the cap is constructed to provide a concavity on its underside thus forming a space for air above the level of the liquid contents even when the can is filled. The spout 40 has its upper wall connecting into said space adjacent the upper end of the concavity as Fig. 1 is viewed. In other words, the upper wall of the spout joins the cap near its center. It is desirable to have the can normally sealed so as to prevent entrance of air and thus to minimize oxidation and other detrimental effect on the contents and since the present cap needs no vent, a tight closure is provided. When the contents is poured from the can the liquid flows over the lower wall of the spout and over the edge 50 while air readily flows into the container by flowing along the upper wall of the spout and into the top portion of the space formed by the concavity.

I claim:

1. A device applicable to containers having an opening for dispensing liquid contents, such as paint, comprising, a closure body for closing said opening, a dispensing spout formation on the closure body, said spout formation being formed at its outlet end so that the lower portion of the outlet has oppositely extending walls which meet each other convergingly at an angle to provide an apex formation, the outlet edges of said walls on opposite sides of the apex each having a relatively sharp knife edge structure, and a closure element for engaging the knife edge structure for closing the spout formation and functioning to sever the stream of the liquid and minimize the accumulation of the particles or drops subsequent to closing.

2. A closure cap and pouring spout unit for attachment to a container for paint or the like, which container has an opening therein, a cap body of concave form on its underside having a peripheral edge formed to seat upon the walls of the container defining said opening, means for holding the cap in position, said closure cap having a pouring spout defined by an upper wall extending upwardly and angularly from approximately the center portion of the body and a lower wall extending upwardly and angularly from approximately the peripheral edge of the body, and wall portions connecting the upper and lower walls to define a pouring spout passage, the lower wall having wall portions the exposed ends of which extend convergingly toward each other and meet at an angle to form an apex in the central lower part of the spout opening, said exposed ends of the said portions being of relatively sharp

knife edge formation, and an operable closure element for the outlet end of the said passage for engaging the knife edge formations to close the spout passage, and serving, together with the sharp edges, to sever the stream of liquid and minimize the accumulation of particles or drops subsequent to closing.

MYRON D. McCUALEY.
